(57) **CLAIM**

The ornamental design for an display screen with a voting wheel icon for a user interface, as shown and described.

DESCRIPTION

FIG. 1 is a front view of a first image in a sequence for a display screen with a voting wheel icon for a user interface; FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof; and,

FIG. 7 is a front view of a seventh image thereof.

The appearance of the animated image sequentially transitions between the images shown in FIGS. 1 to 7.

The process or period in which one image transitions to another image forms no part of the claimed design.

The broken line showing of the display screen in all views is for the purpose of illustrating unclaimed portions of the display screen with a voting wheel icon for a user interface and forms no part of the claimed design.
